UNITED STATES PATENT OFFICE.

JOHN L. LANCASTER, OF WAXAHACHIE, TEXAS.

CHURN.

SPECIFICATION forming part of Letters Patent No. 438,165, dated October 14, 1890.

Application filed August 26, 1889. Serial No. 322,006. (No model.)

To all whom it may concern:

Be it known that I, JOHN L. LANCASTER, a citizen of the United States, residing at Waxahachie, in the county of Ellis and State of 5 Texas, have invented a new and useful Churn, of which the following is a specification.

My invention relates to improvements in churns; and it consists in certain novel features hereinafter described and claimed.

10 In the accompanying drawings, Figure 1 is a perspective view of my improved churn. Fig. 2 is a plan view of the same. Fig. 3 is a detail view of the lid for the churn-body. Fig. 4 is a detail view of the dashers and dasher-rods.

In carrying out my invention I employ a base A, on the upper side of which, near one end of the same, I provide the curved ribs or flanges B, between which the churn-body 20 rests and by which it is prevented from moving when the device is in use. At and near the opposite end of the base I provide the standards C, which are connected at their upper ends by a cross-bar D, and are provided near said upper ends with the right-angled openings E, as shown. The driving-shaft F is journaled in said openings, and is fitted therein by being pushed through the horizontal branches of the same and then allowed to drop to the lower ends of the vertical branches thereof. The driving-shaft is held in the said recesses by the blocks G, which are shaped similar to the recesses and are slipped longitudinally into the same and 35 then secured by any suitable means so as to prevent the driving-shaft rising, as clearly shown. The driving-shaft is provided at its front end with a beveled gear-wheel H and at its rear end with a fly-wheel I, and between 40 the standards C C, I form a crank-arm J on the driving-shaft, and said crank-arm is connected by a pitman K with a treadle L, which is mounted on the base between the standards.

45 On the upper side of the cross-bar D, I secure the dasher-rod-supporting arm, which consists of a stationary member M and a swinging member N, hinged to the stationary member and adapted to fold thereagainst, 50 and the said stationary and swinging members are provided in their meeting edges, near their front or outer ends, with the notches

O, which are adapted to fit around the dasher-rod. The members are held together by a spring-latch P, which is secured to the swinging member and is provided near its end with a perforation Q, adapted to engage a pin R on the upper side of the stationary member. The swinging member is supported when it is turned outward away from the stationary member by a horizontal rearwardly-inclined arm S, secured to the stationary member and provided with a longitudinal slot T, through which the swinging member plays.

I employ two dashers U V, the inner one 65 U consisting of a solid blade or paddle provided with a longitudinal vertical slot at its center and having the dasher-rod X rising from its upper end at the center of the same. The outer dasher is composed of a cross-bar 70 Y, having the depending arms Z at its ends and provided on its upper side with a sleeve a, which encircles the dasher-rod X, as clearly shown. The cross-bar Y is re-enforced by the metallic plates b, secured to its sides so as to 75 prevent its splitting. The tube or sleeve a has a pinion c keyed to its upper end and meshing with the gear-wheel H on the front end of the driving-shaft. The dasher-rod X has a pinion d keyed on its upper portion 80 and meshing with the gear-wheel H, so that the dashers will be rotated in opposite directions.

The churn-body is covered by a lid e, consisting of two semicircular sections having 85 their edges overlapping, and provided with notches f, adapted to fit around the dasher-rod, and the said sections are held together by a link g, having its ends pivoted to the said sections, so that one of said sections may 90 be swung horizontally to and away from the other, and thus permit the lid to be easily fitted around the dasher-rods. The sections are held together while the lid is in place by a spring h, secured to one section and provided at its free end with a perforation i, engaging a pin j on the other section.

In practice the churn-body is filled, either entirely or partially, with cream and is placed in position on the base, after which the 100 treadle is operated in the usual manner to rotate the driving-shaft. The dasher-rods will thus be rotated in contrary directions and the dashers caused to thoroughly agitate the

cream and produce butter. The dashers may be readily adjusted so that one or the other will not be rotated by moving the proper pinion along its key so as to throw it out of mesh with the gear-wheel on the driving shaft. By reason of the peculiar construction of the supporting-arm for the dasher-rods they will be provided with a firm bearing while in use, and can be readily removed when not in use, or when it is desired to clean or repair the churn. The construction of the lid causes it to form a thoroughly dust-proof cover for the churn-body, and at the same time enables it to be conveniently operated.

Having thus described my invention, what I claim, and desire to secure by Letters Patent, is—

1. The combination of the standard, the supporting-arm secured thereon and consisting of a stationary member, a swinging member hinged thereto, a latch secured to the swinging member and engaging the station-

ary member, and the slotted arm secured to the stationary member and passing around the swinging member, and the dasher-rods supported by and between the members of said arms, as set forth.

2. In a churn, the standards, the shaft F, having crank J, combined with the treadle L, having pitman K connected to the crank, the right-angled openings E, having blocks G, the pinion H on shaft F, the dashers, one arranged within the other and driven in opposite directions, the pinion d on one dasher-shaft and the pinion c on the other dasher-shaft, both pinions meshing with the pinion H, as set forth.

In testimony that I claim the foregoing as my own I have hereto affixed my signature in presence of two witnesses.

JOHN L. LANCASTER.
